UNITED STATES PATENT OFFICE.

SAMUEL E. LIVENGOOD, OF CASTANA, IOWA.

CUTTING MECHANISM FOR MOWERS, REAPERS, AND THE LIKE.

1,314,527.

Specification of Letters Patent.

Patented Sept. 2, 1919.

Application filed May 23, 1919. Serial No. 299,252.

To all whom it may concern:

Be it known that I, SAMUEL E. LIVENGOOD, a citizen of the United States, residing at Castana, in the county of Monona and 5 State of Iowa, have invented certain new and useful Improvements in Cutting Mechanism for Mowers, Reapers, and the like, of which the following is a specification.

It is well known in the operation of agricultural machinery embodying cutting mechanism, that the latter becomes clogged and requires frequent cleaning. Means have been devised to facilitate the removal of the cutter bar so that access may be had to the 10 finger bar for removing obstructing matter and also to enable the knife sections to be sharpened when required. Such means have given more or less satisfaction and generally involve a somewhat complex construction.

20 The present invention provides means, whereby the cutter bar may be quickly and conveniently removed and replaced when required because there are no bolts or other fastenings to be removed and when the parts 25 are assembled the cutter bar is securely held against accidental displacement.

The drawing illustrates a preferred embodiment of the invention. However, it is to be understood that in adapting the same 30 to meet different conditions, various changes in the form, proportion, and minor details of construction may be resorted to without departing from the nature of the invention as claimed hereinafter.

35 Referring to the drawing hereto attached, Figure 1 is a top view of a portion of a cutting mechanism embodying the invention.

Figs. 2, 3 and 4 are sectional views on the 40 respective lines 2, 3 and 4 of Fig. 1; and Fig. 5 is a sectional view similar to Fig. 2, parts broken away and showing the elements on a larger scale and the retainer thrown upward into open position.

45 Corresponding and like parts are referred to in the following description and indicated in the several views of the drawing by like reference characters.

The finger bar is of ordinary construction and is provided at its inner end with the 50 usual shoe 2. The guard fingers 3 of ordinary formation are secured to the finger bar 1 in the accustomed way. The cutter bar 4 is slidably mounted on the guard fingers 3

and is provided with the knife section 5. These several parts may be of any well known construction and arrangement and are illustrated to demonstrate the application of the invention.

The retainer consists of a bar 6 which extends the length of the finger bar and is mounted thereon to receive a limited lateral and pivotal movement. A plurality of openings 7 are formed in the bar 6 at intervals in its length and the portions of the bar in the rear of the openings 7 are made rounding, as indicated most clearly in Figs. 2 and 5. Clips 8 secured to the bar 6 have their forward ends engaging the rounded portions of the bar 6 in the rear of the openings 7. The engagement between the bar 6 and clips 8 is such as to admit of the bar 6 having a lateral movement and a pivotal movement, whereby said bar may be engaged with or disengaged from the finger bar and thrown upward, as indicated in Fig. 5, thereby admitting of the cutter bar being removed or placed in position. A plurality of studs 9 depend from the forward edge of the bar 6 and are adapted to enter notches or openings 10 formed in the finger bar. Each of the studs 9 is formed with a notch 11 to engage a portion of the finger bar and act jointly with the clips 8 to prevent vertical movement of the bar 6. The studs 9 are engaged with and disengaged from the finger bar by means of a lateral movement of the retainer bar 6. A forward movement of the retainer bar 6 disengages the studs 9 from the finger bar. A rearward movement of the retainer bar 6 engages the studs 9 with the finger bar.

Lock means are provided for securing the retainer bar 6 in operative position. The locking means consist of flat springs 12 and studs 13 at the free ends of the springs 12, 95 said studs being adapted to pass through openings *a* formed in the retainer bar 6 and enter registering openings formed in the finger bar. This is indicated most clearly in Fig. 4. Each of the springs 12 is pivotally connected at one end as indicated at 14 with the retainer bar 6, so that when the end of the spring provided with the stud 13 is drawn outward it may be moved laterally to engage the stud 13 with the bar 6 at one 100 side of the opening and thereby hold the

stud 13 clear of the opening, as indicated in Fig. 5, whereby the retainer bar 6 may be moved laterally and swung upwardly so as to clear the cutter bar and admit of the same being removed from the finger bar, either for sharpening or for clearing the parts of grass or other obstructing matter.

Projections 15 extend forwardly from the retainer bar 6 and overhang the cutter bar, thereby holding it in position on the finger bar. The projections 15 may form a part of the bar 6 or may be attached thereto in any manner. The studs 9 are located at the rear ends of the projections 15 so as to coöperate therewith and prevent possible movement thereof when the retainer is in operative position and made secure by the fastening means.

When it is required to remove the cutter bar, the free ends of the springs 12 are drawn upward and swung laterally, thereby releasing the retainer bar 6 which is moved forwardly to disengage the studs 9 from the finger bar after which the bar 6 and attached parts are swung upwardly, as indicated in Fig. 5, thereby releasing the cutter bar, which is moved to bring the cutter sections opposite the spaces between the guard fingers when the cutter is removed by elevating the bar 4 to disengage it from the finger bar after which said cutter bar is moved rearwardly, thereby clearing the knife sections from the guard fingers. The reverse of this operation is practised when placing the cutter bar in position, the same being made secure by swinging the retainer into horizontal position and moving the bar 6 rearwardly to engage the studs 9 with the finger bar, said retainer being made secure by swinging the springs 12 to cause the studs 13 to aline with the registering openings in the retainer and finger bars. When the studs 13 enter the registering openings in the bars 6 and 1, the retainer is prevented from lateral movement and is held in place by the studs 9 and the clips 8.

The foregoing description and the drawing have reference to what may be considered the preferred, or approved form of my invention. It is to be understood that I may make such changes in construction and arrangement and combination of parts, materials, dimensions, et cetera, as may prove expedient and fall within the scope of the appended claims.

Having thus fully described my invention, what I claim as new and desire to secure by Letters Patent is:

1. In cutting apparatus of the character specified, comprising a finger bar and a cutter bar, a retainer for holding the cutter bar in place upon the finger bar, locking means between the retainer and finger bar adapted to be engaged and disengaged by a relative sliding movement of the retainer, and means

for securing the retainer in operative position, the same consisting of a spring secured at one end to the retainer and provided at its opposite end with a stud to enter registering openings formed in the retainer and finger bar. 70

2. In cutting apparatus of the character specified, and in combination with the usual finger bar and cutter bar, a retainer mounted on the finger bar and having a lateral and 75 a pivotal movement, fastening means between the retainer, and finger bar adapted to be engaged and disengaged by the lateral movement of the retainer and means for securing the retainer against lateral movement when in operative position. 80

3. In cutting apparatus of the character set forth, comprising coöoperating finger and cutter bars, a retainer mounted upon the finger bar and having a pivotal and a lateral 85 movement, notched studs carried by the retainer and adapted to be engaged with and disengaged from the finger bar by the lateral movement of the retainer and means for preventing lateral movement of the retainer when in operative position. 90

4. In cutting apparatus of the character specified, comprising finger and cutter bars, a retainer mounted on the finger bar and adapted to receive a lateral and a swing- 95 ing movement, clips forming connecting means between the finger bar and retainer, studs carried by the retainer and engageable with and disengageable from the finger bar by the lateral movement of the retainer and 100 acting jointly with the said clips to secure the retainer in operative position and means for preventing lateral movement of the retainer when in operative position. 105

5. In cutting mechanism of the character specified, including finger and cutter bars, a retainer bar mounted upon the finger bar and having a lateral and a swinging movement, clips secured to the finger bar and engaging the retainer, studs carried by the re- 110 tainer and engageable with and disengageable from the finger bar by the lateral movement of the retainer and coöperating means between the retainer and finger bar for preventing lateral movement of the retainer 115 when in operative position. 115

6. In cutting mechanism, comprising finger and cutter bars, a retainer bar mounted on the finger bar and having projections overhanging the cutter bar, studs carried by the retainer bar and adapted to be engaged with and disengaged from the finger bar by means of a lateral movement of the retainer bar and coöperating means between the retainer bar and finger bar to secure the retainer bar against lateral movement when in operative position. 120

7. In cutting apparatus, comprising finger and cutter bars, a retainer mounted on the finger bar and adapted to have a slid- 125 130

ing and swinging movement imparted thereto, fastening means between the retainer and finger bar adapted to be engaged and disengaged by the sliding movement of the
5 retainer and other fastening means for securing the retainer against sliding movement when in operative position.

In testimony whereof I affix my signature in presence of two witnesses.

SAMUEL E. LIVENGOOD.
